CLAIM

The ornamental design for a mounting for attaching a
flashlight to a tubular support structure such as a gun
barrel, as shown and described.

DESCRIPTION

FIG. 1 is a front perspective view of a mounting for
attaching a flashlight to a tubular support structure such
as a gun barrel showing my design;

FIG. 2 is a front elevational view, the rear being a mir-
ror image thereof;

FIG. 3 is a top plan view;

FIG. 4 is a bottom plan view;

FIG. 5 is a side elevational view, both sides being sub-
stantially identical;

FIG. 6 is a side elevational view shown inverted from
FIG. 2, the flashlight and tubular support being shown
in broken lines for illustrative purposes only.
